1 Claim. (Cl. 200—131)

The invention relates to fuse-links.

According to this invention there is provided a fuse link comprising a tubular ceramic body, defining a cylindrical bore, two metallic end caps secured to and embracing the opposite ends of the body to seal the said bore, a single fusible wire substantially circular in cross-section connected to said end caps and extending therebetween substantially centrally within the tubular body, and a plurality of cylindrical ceramic discs located within the said bore and making heat-conductive contact with the body over their outer periphery, the beads together defining an aligned bore through which said fusible wire extends and making heat-conductive contact with said fusible wire at a plurality of spaced positions along its length intermediate the said end caps whereby to increase the heat dissipated from said portions relatively to the remaining portions of said fusible wire in response to the passage of current therethrough.

One example of a fuse link embodying this invention will now be described with reference to the accompanying drawing in which the figure shows a sectional elevation of the fuse link.

Referring now to the figure, the fuse link comprises a tubular ceramic body 10 having metallic end caps 11 between which a fuse element 20 comprising a single wire 35 of circular cross-section, is connected. This fuse element extends through aligned holes in four ceramic discs or beads 50 which are mounted in the fuse body 10. The discs are in physical contact with both the fuse body 10 and with central portions 51 of the fuse-element 20 and 40 are the means of increasing the heat transfer from the central fuse-element portions 51. More particularly, it will be apparent that without these heat-conducting discs in contact with the central portions of the fuse element the rate of heat generation there will be much greater than in the remaining end portions since heat is lost from these latter portions by conduction in the end caps, whereas by placing such heat conductors in contact with these central portions the rate of heat loss from the element may be carefully controlled along its length. The discs 50 50 may be varied in thickness, position, and number to achieve particular characteristics of the fuse.

2

The invention enables fuse-links to be produced which, at any given current, rupture at a later time than would a comparable normal high-rupture-capacity (H.R.C.) fuse-link in which a filler is interposed between the fuse-element and the fuse body, or would a comparable fuse-link in which a uniform fuse-element is uniformly spaced from the fuse body. It also enables the time required, at any given current, before rupture takes place to be easily controlled. A fuse-link embodying the invention may thus have a more precise time-current characteristic which is advantageous in certain applications.

What we claim as our invention and desire to secure by Letters Patent is:

A fuse link comprising
a tubular ceramic body defining a cylindrical bore,
two metallic end caps secured to and embracing the
opposite ends of the body to seal the said bore,
a single fusible wire substantially circular in cross-
section connected to said end caps and extending
therebetween substantially centrally within the tubu-
lar body, and
a plurality of cylindrical ceramic discs disposed along
a common axis within the said bore and making
heat-conductive contact with the body over their
outer periphery, the discs together defining an
aligned bore through which said fusible wire extends
and making heat-conductive contact with said fusible
wire at a plurality of spaced positions along its
length, said discs being confined to the central por-
tion of said tubular body intermediate the said end
caps whereby to increase the heat dissipated from
said portions relatively to the remaining portions of
said fusible wire in response to the passage of cur-
rent therethrough.
